Design No. 12,227, dated April 19, 1881.

UNITED STATES PATENT OFFICE.

CHARLES H. BUCK, JR., OF ST. LOUIS, MISSOURI.

DESIGN FOR A HEATING-STOVE.

SPECIFICATION forming part of Design No. 12,227, dated April 19, 1881.

Application filed March 14, 1881. Term of patent 3½ years.

To all whom it may concern:

Be it known that I, CHARLES H. BUCK, Jr., a citizen of the United States, residing in the city of St. Louis, Missouri, have invented and 5 produced a new and original Design for Heating-Stoves, of which the following is a specification, reference being had to the accompanying engraving, forming part thereof, in which the stove in question is shown in perspective.

The leading feature of my design consists in the peculiar form of hearth at the side of the stove, substantially as hereinafter more fully described.

15 In the annexed engraving, A represents a stove having the feature in question, and, saving which feature, is of the design patented the 11th January, 1881.

B represents the hearth. It is at the side of the stove, and is scalloped as shown at *bb*. 20 The base C beneath the hearth is arched, and also scalloped at *cc* to correspond in outline to the hearth.

I claim—

1. The design for a heating-stove herein 25 shown and described, the same consisting of the hearth B, scalloped and arranged as described.
2. The design for a heating-stove herein shown and described, the same consisting of 30 the base C, arched and scalloped as described.

C. H. BUCK, JR.

Witnesses:

CHAS. D. MOODY,
CHARLES PICKLES.
